UNITED STATES PATENT OFFICE.

DORA MITCHELL, OF OTTUMWA, IOWA.

PICTURE-HANGER.

SPECIFICATION forming part of Letters Patent No. 351,932, dated November 2, 1886.

Application filed June 2, 1886. Serial No. 208,914. (No model.)

To all whom it may concern:

Be it known that I, DORA MITCHELL, of Ottumwa, in the county of Wapello and State of Iowa, have invented a new and Improved Picture-Hanger, of which the following is a full, clear, and exact description.

My invention relates to an implement designed for hanging and taking down pictures, and has for its object to provide a simple, inexpensive, light, strong, and efficient device of this character.

The invention consists in certain novel features of construction and combinations of parts of the picture-hanger, all as hereinafter fully described and claimed.

Reference is to be had to the accompanying drawings, forming a part of this specification, in which similar letters of reference indicate corresponding parts in both the figures.

20 Figure 1 is a perspective view of the picture-hanger and a picture-nail and part of a picture-cord, and illustrates the use of the implement; and Fig. 2 is an elevation of the lower end of the hanger, showing its use in adjusting a picture-cord hook.

The pole or staff A of the picture-hanger may be made of one piece of hard wood of any necessary length; but I prefer to make the pole in two sections, a', hinged together by 30 a rule-joint, a², and provided with a hook, B, and eye b, for holding the pole extended, as in Fig. 1, when the device is in use, and allowing the pole to be folded into small space to stow it away. One end of the pole is widened considerably, and to this end is attached strongly by a tongue-and-groove joint a metal head-piece, C, which is provided with opposite forked ends, consisting each of a long prong, c, and a shorter prong, c', and between these 40 forked ends the head-piece is concaved, at c², for quite a little distance below the points of junction of the prongs of the end forks of the head-piece. With this construction the loop of a wire or cord, D, attached to a picture or 45 its frame may be hung between the prongs c c' of the forked ends of the head-piece C, and the pole may be lifted to allow the picture-cord to be hung upon a nail, E, driven into the wall of a room, the concavity c² of the 50 head-piece allowing the head of the picture nail or hook to enter below or within the loop of the cord. To unhang or remove a picture, the longer prongs, c c', of the head-piece will be laid against the wall, and the implement will 55 be raised to catch the picture wire or cord D

in the prongs of the head-piece, and the cord then may be lifted from the picture nail or hook, all as will be understood from Fig. 1 of the drawings. At the other end of the pole A there is fitted by a tongue-and-groove joint 60 a spring-clamp, F, between the opposing elastic jaws f f of which the lower end, g, of a picture-hook, G, may be held, to allow the hook to be placed onto a molding nailed to the wall of a room, when pictures are to be 65 hung in this way instead of by ordinary picture-nails. When the upper end, g', of the hook is engaged with the molding, the pole A will be pulled downward, and the spring-clamp F will draw away from the hook, leaving it on 70 the molding, and the other end or head-piece, C, of the hanger then may be used to hang a picture by slipping its cord or wire into the lower end, g, of the hook, all of which may quickly and easily be done.

By making the prongs c c of the head-piece C longer than the other prongs, c' c', a picture may be hung or taken down with assurance of its safety, as there is little or no danger of the picture cord or wire slipping from the prongs, 80 and at the same time the metal head-piece C is made lighter than it otherwise would be; and the less weight a device of this kind has, with ample strength for its work, the more easily it may be handled with safety to the 85 pictures.

Both the head-piece C and the spring-clamp F are held to the pole A by rivets, screws, or nails H, passed through the tongue-and-groove joints of the head-piece, and clamp with the 90 pole; but any other suitable fastening may be adopted.

Having thus described my invention, what I claim as new, and desire to secure by Letters Patent, is—

95 1. A picture-hanger comprising a pole, a double-forked head-piece fixed to one end of the pole, and a spring-clamp fixed to the other end of the pole, substantially as described, for the purposes set forth.

2. A picture-hanger comprising a pole made in sections hinged together and provided with a fastening at the joint, and a double-forked head-piece fixed to one end of the pole and a spring-clamp fixed to the other end of the 105 pole, substantially as herein set forth.

DORA MITCHELL.
